UNITED STATES PATENT OFFICE.

GEORGE W. COMBS, OF LEAVENWORTH, KANSAS.

GYRATORY STRUCTURE.

1,123,167.

Specification of Letters Patent. Patented Dec. 29, 1914.

Application filed September 24, 1907. Serial No. 394,330.

To all whom it may concern:

Be it known that I, GEORGE W. COMBS, a citizen of the United States, residing at Leavenworth, in the county of Leavenworth and State of Kansas, have invented certain new and useful Improvements in Gyratory Structures, of which the following is a specification.

My invention relates to improvements in 10 gyratory structures; and pertains more particularly to the driving mechanism whereby a gyratory motion is imparted to the structure.

My principal object is to relieve the building 15 containing the structure of the vibration to which it is subjected when the driving mechanism in general use is employed. The mechanism whereby I attain this object includes a shaft mounted in the structure, 20 a fixedly mounted driver surrounding the axis of movement, a support for the shaft independent of the structure and the driver, and a yielding connection between the shaft and the driver so that said shaft is capable 25 of the slight movement necessary to relieve the building from the strain to which it would be subjected in operation, especially, when starting or stopping the structure, such as is incident to a rigid connection 30 between the building and the gyratory structure.

Referring now to the accompanying drawings, which illustrate the invention: Figure 1 shows a vertical section of a gyratory sifter on line I—I of Fig. 2, provided with my improvements. Fig. 2 is a plan view of the same with the resilient rods removed and the shaft in section on line II—II of Fig. 1. Fig. 3 is a plan view of an overhead support for the shaft. Fig. 4 is a vertical section on line IV—IV of Fig. 3. Fig. 5 is a vertical section of the driver and the yielding connection between it and the shaft. Fig. 6 is an enlarged vertical section on line 45 VI—VI of Fig. 5. Fig. 7 is a side elevation of a modified form of the sifter and the drive mechanism. Fig. 8 is an end view of the same partly in section. Figs. 9 and 10 are vertical sections on lines IX and X, respectively, of the modified form of drive mechanism. Fig. 11 is a detail view of a yielding-coupling, forming part of the modified drive mechanism for connecting the driver to the shaft.

55 In the preferred form, Figs. 1 and 2, the gyratory structure 1 consists of four sieve-

boxes 2 connected in diagonal pairs of diagonally-arranged bridge-trees 3 and supported by resilient rods 4 from a suitable point overhead. With this construction the sieve-boxes balance each other so that the heavy balance-weights usually employed for this purpose may be dispensed with. Bridge-trees 3 are provided with centrally-disposed bearings 5, in which I mount a shaft 6 having a set of cranks 7 journaled in one set of bridge-trees, while the main body of shaft 6 is journaled in the other set of bridge-trees, said cranks and body portion being arranged equal distances at opposite sides of the axial line of movement, so that when the shaft is rotated it will impart a gyratory motion to the sieve-boxes.

8 designates a pin secured at its lower end to the upper end of the shaft by a hub 9 and so positioned as to constitute the center of rotation when the parts are in motion and working normally. The shaft revolves around this pin, the distance between the axis of the pin and the axis of the shaft being the radius of the orbit of gyration. Pin 8 is supported by a bearing secured to an adjacent portion of the building and consisting of a bearing-block and a base which latter has a chamber 21 in which the former is loosely mounted. The bearing-block consists of a self-adjusting member 10 and a sliding member 11, the former of which has a lower curved end that fits in a correspondingly curved seat 13 in the latter, so that pin 8 may adjust itself to a perpendicular position should base 12 for any reason get slightly out of its proper position.

As will be noted, member 11 has no fixed connection with the surface on which it rests, and may therefore slide somewhat, over said surface, in case of any irregularity of movement, being restrained only by reason of the friction between the parts. The side walls of chamber 21 are only for the purpose of retaining a lubricant, and are sufficiently distant from the engaging portion 23 of the bearing-block so that the latter does not come in contact with said walls. The movement of said block is therefore not limited except by the friction between it and the adjacent surface and the nature of the apparatus. Said adjacent surface, or chamber-bottom, is preferably flat, as shown in Fig. 4; but may be concave, if desired, as shown in Figs. 9 and 10.

In order that the rotation of the pin will

be attended with but little friction, I provide it with a fixed collar 14 which rests upon balls 15, arranged to travel upon a hardened ring 16 set in member 10. The ball-bearing 5 thus produced is submerged in a lubricant placed in chamber 19 in the upper portion of member 10, said member being provided with a cap 20 to exclude dust from said chamber. The upper end of pin 8 has 10 screw-threads 17, whereby it is adjustably engaged by collar 14, and a pair of lock-nuts 18. This permits the pin and the shaft to be adjusted vertically to their proper positions and also admits taking up any 15 lost motion which may be occasioned by wear of the different parts.

24 designates a drive-pulley which is mounted in a step-bearing 26 secured to an adjacent portion of the building (as the 20 floor), the pulley being thus free from connection with the structure which it is designed to drive, except by the means which will presently be described.

The lower end of shaft 6 is provided 25 with a hub 27, in which is secured an extension 28 connected at its lower end to a universal-joint 29, carrying a short pin 30, slidingly engaging the upper portion of a universal-joint 31, which extends down into 30 and is connected with the large hollow hub 32 of the drive-pulley 24. The wall of hub 32 is extended upward for the purpose of retaining a lubricant, and is sufficiently distant from the universal-joint 31 to prevent 35 the latter from contacting with said wall. By permitting pin 8 to slide laterally and yieldingly-connecting the shaft to the drive-pulley it is obvious that any irregular motion of the shaft and the suspended structure will not be imparted to the building. The short pin 30 is provided at its lower 40 end with a feather 33, so that it slidingly engages and is turned by the universal-joint 31, hence should the shaft gyrate by 45 reason of abnormal throw of the gyratory structure, pin 30 may slide upward and thus allow for the gyratory movement of the shaft.

Referring now to the modification, shown 50 in Figs. 7 to 11, inclusive, 1^a designates the gyratory structure, which, in this instance, consists of two sieve-boxes 2^a connected by bridge-trees 3^a and supported by resilient rods 4^a. Bridge-trees 3^a are provided with 55 bearings 5^a, in which is mounted a shaft 6^a, carrying at its ends weights, as 7^a, the center of gravity being thus situated at one side of the axis of the shaft, so that when the shaft is moved the desired gyratory movement of the structure to which it is attached may be secured. These weights may 60 be of any desired size or character. Plain solid weight-arms are shown. 24^a designates the drive-pulley which is mounted in 65 a step-bearing 26^a, so that the pulley will

be free from connection with the gyratory structure except by the means hereinafter described. This pulley has a large hollow hub 32^a forming a chamber which contains a loosely mounted bearing-block consisting 70 of a self-adjusting member 10^a and a sliding member 11^a, the former being loosely mounted in the latter so that it will always be at right angles with a pin 8^a, the lower end of which rests thereon. Balls 15^a are 75 interposed between the end of the pin and the self-adjusting member to reduce the friction between these parts. Pin 8^a is secured to the lower end of shaft 6^a by means of a hub 27^a, which in the present instance 80 is a part of the lowermost weight-arm. The bearing-block rests upon a base 12^b fixed to the upper end of a stub-shaft 25^a secured in the step-bearing 26^a. As the bearing-block has no fixed connection with 85 the base 12^b it is free to slide thereon in case the shaft should slightly gyrate before the machine has attained its regular movement, being restrained only by reason of the friction between the parts. The face of 90 base 12^b is concaved so that the friction between it and the bearing-block will increase in proportion to the lateral movement of the latter. Connection is made between the drive-pulley and the pin 8^a by a yielding-coupling consisting of an upper plate 35, an intermediate plate 36, and a lower plate 37. Plate 35, which is shown in an inverted position in Fig. 10, is keyed to the lower portion of pin 8^a and provided at its under-side with a pair of diametrically-opposed ribs 38, which slidingly engage the walls of a corresponding pair of grooves 39 in the upper surface of plate 36, which latter is provided with a pair of diametrically-opposed ribs 40 arranged at right angles to grooves 39. Ribs 40 slidingly engage the walls of a pair of grooves 41 in the upper surface of plate 37, which latter is secured to hub 32^a of the drive-pulley. By inserting this coupling between pin 8^a and the drive-wheel it is obvious that when the latter is rotated it will impart a rotary movement to said shaft, and cause said shaft and the parts connected thereto to travel about 100 the axis indicated by the pin 8^a.

Having thus described my invention, what I claim and desire to secure by Letters Patent, is—

1. In combination, a suspended structure, suspending means therefor, a shaft mounted in said structure, a fixedly mounted driver surrounding the axis of movement, a support for said shaft independent of said structure and said driver, and a yielding connection independent of the suspending means between the suspended structure and the driver whereby said structure is permitted a gyratory movement in operation.

2. In combination, a suspended body, a

shaft arranged centrally therein and weighted to produce a gyratory movement, a pin set eccentrically to said shaft and extending downwardly and resting in a step-bearing whereby the weight of said shaft and its weights are supported, a driver having a central opening into which said pin extends but free of contact therewith, and a bearing in which said driver is mounted adjacent to the step-bearing carrying the pin.

3. In combination, a suspended structure arranged to have a gyratory movement, a driver mounted in a stationary bearing carried on an adjacent portion of the building, said driver having a central opening of considerable size, a shaft mounted in the suspended structure, and a pin set eccentric to said shaft, but secured thereto and extending down into the opening in the driver, and a step-bearing for said pin.

4. In combination, a suspended structure arranged to have a gyratory movement, a driver mounted in a stationary bearing carried on an adjacent portion of the building, said driver having a central opening of considerable size, a shaft mounted in the suspended structure, and a pin set eccentric to said shaft but secured thereto and extending down into the opening in the driver, and a step-bearing for said pin consisting of a suitable block slidably mounted on a base.

5. In combination, a suspended body, suspending devices therefor, means for giving said body a gyratory movement, a stationary driver, a shaft to said suspended body, a support for said shaft independent of said driver, and a yielding connection between said driver and the shaft of said suspended body whereby they are engaged for coincident rotation but permitting a relative movement equal to the distance between the axis of rotation and the axis of gyration.

6. In combination, a suspended structure arranged to have a gyratory movement, a driver therefor, a shaft mounted therein, a pin set eccentric to said shaft, a step-bearing for said pin carrying the weight thereof and of the shaft, said step-bearing being free to move over the surface of the support on which it rests.

7. In combination, a suspended structure arranged to have a gyratory movement, a driver therefor, a shaft mounted in bearings engaging with said suspended structure, a pin set eccentric to said shaft, and a chamber adapted to contain a lubricant and which is larger than said pin into which the lower end of said pin enters and upon the bottom of which it is supported and adapted to move.

8. In combination, a suspended structure arranged to have a gyratory movement, a driver therefor, a shaft thereto, a pin whose axial line is different from that of the shaft

but operatively connected therewith, and a support upon which said pin rests having a friction surface over which said pin may move, whereby said pin and the parts carried thereby are frictionally restrained and the weight thereof supported.

9. In combination, a suspended structure arranged to have a gyratory movement, a driver therefor, a shaft thereto, a pin whose axial line is different from that of the shaft but operatively connected therewith, a support upon which said pin rests having a friction surface over which said pin may move, and a bearing-block interposed between said pin and the surface of said support.

10. In combination, a suspended structure arranged to have a gyratory movement, a driver therefor, a shaft thereto, a pin whose axial line is different from that of the shaft but operatively connected therewith, and a support upon which said pin rests having a friction surface over which said pin may move, said surface being surrounded by a wall thus forming also a lubricant chamber.

11. In combination, a suspended structure arranged to have a gyratory movement, a driver therefor, a shaft thereto, a pin set eccentric to said shaft, and frictional means coacting with the eccentric pin for restraining abnormal throw of the suspended structure during gyration.

12. In combination, a suspended structure arranged to have a gyratory movement, a driver therefor, a shaft mounted in bearings engaging with said suspended structure, a pin whose axial line is different from that of the shaft but operatively connected therewith, and frictional means supporting the weight of the pin and parts carried thereby and coacting with said pin for restraining abnormal throw of the structure during gyration.

13. In combination, a suspended structure, a fixedly mounted driver surrounding the axis of movement, a shaft in said structure, a pin whose axial line is different from that of the shaft but operatively connected therewith, a support upon which said pin rests, and a frictional device coacting with said pin for restraining abnormal throw of the structure during gyration.

14. In combination, a suspended structure, suspending means therefor, a shaft mounted in said structure, a support for said shaft independent of said structure, a self-adjusting member between the shaft and said support, a driver, and a yielding connection between the suspended structure and the driver whereby said structure is permitted a gyratory movement in operation.

15. In combination, a suspended structure carrying a shaft, weights connected with said shaft whereby it is given a tendency when in motion to travel in a gyratory path,

1. A fixedly-mounted driver surrounding the axis of movement, a support for the shaft independent of the driver, a self-adjusting connection between the shaft and the support, and a yielding connection independent of the suspending means between the shaft and the driver.
2. In combination, a suspended body, a vertically-positioned shaft therein weighted to produce a gyratory movement, a pin connected to said shaft, a support for said pin, a self-adjusting member between the pin and said support, and a driver mounted in a fixed bearing adjacent to the end of the shaft and surrounding the axis of movement.
3. In combination, a suspended body, a shaft arranged centrally therein and weighted to produce a gyratory movement, a pin secured to said shaft and extending through a base whereby the weight of the shaft and its weights are supported, a self-adjusting connection between the pin and said base, a driver, and a yielding connection independent of the suspending means between the suspended structure and the driver whereby said structure is permitted a gyratory movement in operation.
4. In combination, a suspended structure arranged to have a gyratory movement, a driver mounted in a stationary bearing carried on an adjacent portion of the building, said driver having a central opening of considerable size, a shaft mounted in the suspended structure, a pin secured to said shaft and extending down into the opening in the driver, a step-bearing, and a self-adjusting connection between the pin and said step-bearing.
5. In combination, a suspended body, a shaft arranged centrally therein, a driver yieldingly connected to said shaft, a pin also secured to said shaft, a base, a sliding member free to move on said base, and a self-adjusting connection between the pin and said sliding member.
6. In combination, a suspended body, suspending devices therefor, means for giving said body a gyratory movement, a stationary driver, a shaft to said suspended body, a support for said shaft independent of said driver, a self-adjusting member between the shaft and said support, and a yielding connection between said driver and the shaft of said suspended body whereby they are engaged for coincident rotation by permitting a relative movement equal to the distance between the axis of rotation and the axis of gyration.
7. In combination, a suspended structure arranged to have a gyratory movement, a driver therefor, a shaft mounted therein, a pin secured to said shaft, a bearing for said pin carrying the weight thereof and of the shaft, said bearing being free to move over the surface of the support on which it rests, and an adjustable member between the pin and said bearing.
8. In combination, a suspended structure arranged to have a gyratory movement, a driver therefor, a shaft thereto, a pin connected to said shaft, a support for said pin having a frictional surface whereby said pin and the parts carried thereby are frictionally restrained and the weight thereof supported and a self-adjusting connection between the pin and said support.
9. In combination, a suspended structure arranged to have a gyratory movement, a driver therefor, a shaft mounted in bearings engaging said suspended structure, a pin secured to said shaft, a base containing a lubricant chamber, a sliding member mounted on said base and adapted to support the weight of the shaft, and a self-adjusting connection between the pin and said sliding member.
10. In combination, a suspended structure arranged to have a gyratory movement, a driver, a shaft thereto, a pin secured to said shaft, frictional means coacting with said pin for restraining abnormal throw of the structure during gyration, and a self-adjusting member between the pin and said frictional means.
11. In combination, a suspended structure, a fixedly-mounted driver surrounding the axis of movement, a shaft in said structure, a pin operably-connected to said shaft, a support for said pin, a frictional device coacting with said pin for restraining abnormal throw of the structure during gyration, and an adjustable member between the pin and said frictional device.
12. The combination, in a gyratory sifter, of a sifter body, means whereby the same is suspended, bearings arranged centrally of said body, an eccentrically-weighted shaft mounted in said bearings, a pin on said shaft, a bearing supporting said pin and through it said weighted shaft, a self-adjusting member between the pin and said bearings, a fixedly-mounted driver, and a yielding connection between the shaft and said driver.
13. In combination, a suspended structure arranged to have a gyratory movement, a driver therefor, a shaft thereto, a base having a curved surface, a sliding member having a curved surface resting in the curved surface of said base and adapted to coact with the pin for restraining abnormal throw of the structure during gyration, and a self-adjusting connection between the shaft and said sliding member.
14. In combination, a suspended structure arranged to have a gyratory movement, a driver therefor, a shaft thereto, a base, a sliding member thereon which coacts with the shaft for restraining abnormal throw of the structure during gyration, and a self-adjusting member between the pin and said bearing.

- adjusting connection connecting the shaft and the sliding member, said connection having a lubricant chamber surrounding the adjacent portion of the shaft.
- 5 29. In combination, a suspended structure, means for giving the same a gyratory movement, a stationary driver, and yielding means connecting the shaft of the suspended structure and said driver, consisting of a member fixed to the driver, a second member slidingly mounted upon the first-mentioned one, and a third member on the second member adapted to slide at right angles thereto, said third member being fixed to the shaft.
- 10 30. In combination, a gyratory structure, a stationary driver, a step-bearing on which the shaft of the suspended structure rests, and yielding means connecting the driver and said shaft, consisting of a member fixed to the driver, a second member movable upon the first-mentioned one, and a third member movable on the second member and secured to the shaft, all of said members having openings through which the lower 25 end of the shaft extends.
31. In combination, a suspended structure arranged to have a gyratory movement, a stationary bearing, a driver mounted thereby, said driver having a central opening, laterally movable rotatable means including a shaft engaging the suspended structure, said rotatable means extending through the opening in the driver, and a step bearing for said rotatable means.
- 35 32. In combination, a suspended structure arranged to have a gyratory movement, a stationary bearing, a driver mounted thereby, said driver having a central opening, laterally movable rotatable means including a shaft for actuating the suspended structure, said rotatable means extending through the opening in the driver, and a step bearing for said rotatable means.
33. In combination, two pairs of diagonally connected containers arranged to have a gyratory movement, a shaft mounted therein, a driver for said shaft, a stem to said shaft, a step-bearing for said stem, carrying the weight thereof and of the shaft, and a support for said step-bearing over the surface of which it is free to move.
- 45 34. In combination, two sets of diagonally connected containers, a rotary vertical shaft eccentrically connected to said containers to gyrate the same, said shaft being free to move laterally in any direction, a driver therefor, a stem to said shaft, a step-bearing for said stem carrying the weight thereof and of the shaft, and a support for said step-bearing over the surface of which it is free to move.
- 50 35. In combination, two pairs of diagonally connected containers, a vertical shaft having oppositely disposed cranks connected to each pair of containers to impart gyra-
- tory motion thereto, a driver therefor, a stem to said shaft, a step-bearing for said stem, carrying the weight thereof and of the shaft, and a support for said step-bearing over the surface of which it is free to move 70 laterally in any direction.
36. In combination, two sets of diagonally connected containers, arranged to have a gyratory movement, a driven shaft mounted therein, said containers and shaft being 75 capable of lateral movement in any direction, a stem to said shaft, and a step-bearing for said stem.
37. In combination, two sets of diagonally connected containers, a shaft arranged 80 therein, a stem to said shaft extending downwardly, a step-bearing for said stem, a fixedly-mounted driver surrounding the axis of rotation and operably-connected to the stem, and a bearing in which said driver 85 is mounted adjacent to said step-bearing.
38. In combination, two sets of diagonally connected suspended containers, a vertical rotary shaft free to move horizontally and eccentrically connected to said containers, a stem to said shaft extending downwardly, a step-bearing supporting said stem, a fixedly-mounted driver surrounding the axis of rotation and operably-connected to the stem, and a bearing in which said driver 90 is mounted adjacent to said step-bearing.
39. In combination, a gyratory body, a shaft arranged therein, and weighted to produce a gyratory movement, a stationary driver for said shaft, and a support for said shaft having a universal connection therewith.
40. In combination, a gyratory body, a shaft arranged therein and weighted to produce a gyratory movement, a support for 105 said shaft, a stationary driver, a shaft for said driven, and a universal connection between said shafts.
41. In combination, a structure arranged to have a gyratory movement, a shaft mounted in bearings engaging with said structure, weights secured to said shaft, a stationary driver for said shaft, and a support for said shaft having a universal connection therewith. 110
42. In combination, a gyratory body, a crank shaft arranged therein, a stationary driver, a shaft therefor, and a support for said crank shaft having a universal connection between the same and said driver. 115
43. In combination, a gyratory body, a crank shaft arranged therein, weighted means thereon, a stationary driver operably-connected to said crank shaft, and a support for said crank shaft having a universal connection therewith. 120
44. In combination, a gyratory body, a crank shaft arranged therein, weighted means thereon, a stationary driver, a shaft for said driver, and a universal connection 125

- between the driver shaft and said crank shaft.
45. In combination, a gyratory body, a crank arranged therein, weighted means thereon, a stationary driver, a shaft for said driver, a universal support for said crank shaft carried by the driver shaft, and a universal driving connection between the stationary driver and the crank shaft.
- 10 46. In combination a gyratory body, a crank shaft arranged therein, weighted means thereon, a stationary driver, a shaft therefor, a support for said crank constituting a universal connection between said shafts, and a universal connection between the stationary driver and the crank shaft.
- 15 47. In combination, a gyratory body, a shaft arranged therein, weighted means thereon, a stationary driver, a shaft therefor, and a support for said shaft having a universal connection between the same and said driver shaft.
- 20 48. In combination a gyratory structure, a shaft thereto, a driver therefor, and frictional restraining means whereby abnormal throw of the structure is restricted.
- 25 49. In combination a gyratory structure, a shaft thereto, a stationary driver therefor, and frictional restraining means whereby abnormal throw of the structure is restricted.
- 30 50. In combination, a gyratory body, suspending devices therefor, a shaft for actuating said gyratory body, a driver for said shaft, a support for said shaft independent of said driver, and a yielding connection between said driver and the shaft whereby they are engaged for coincident rotation but permitting a relative movement equal to the distance between the axis of rotation and the axis of gyration.
- 35 51. In combination, a gyratory body, suspending devices therefor, a shaft for actuating said gyratory body, a driver for said shaft, a support for said shaft independent of said structure, and a yielding connection between said driver and the shaft whereby they are engaged for coincident rotation but permitting a relative movement equal to the distance between the axis of rotation and the axis of gyration.
- 40 52. In combination, a gyratory structure freely supported, a suspended drive shaft for actuating said gyratory structure, means for driving said shaft having a stationary bearing, and a bearing member in which said shaft is journaled, said bearing member having universal motion.
- 45 53. In combination, a gyratory structure freely supported, a suspended drive shaft for actuating said gyratory structure, a driver for said shaft, a bearing member free to move universally and in which said shaft is journaled, and a socket member for said bearing member free to move laterally and orbitally.
54. In combination, a gyratory structure, a suspended shaft for actuating said gyratory structure, means for driving said shaft, a bearing in which said shaft is journaled, a 70 socket member for said bearing member free to move laterally in any direction, a cap on the shaft, and an antifriction thrust bearing between said bearing member and the cap, whereby the shaft is suspended for free rotation in said bearing member while the latter is free to move universally.
55. In combination, two sets of diagonally connected containers, a suspended drive shaft for actuating said containers, a 80 driver for said shaft, a bearing member free to move universally and in which said shaft is journaled, a socket member for said bearing member, a cap on the shaft, an antifriction thrust bearing between said bearing 85 member and the cap, and a dust cap covering the first-mentioned cap and the antifriction thrust bearing.
56. In combination, two sets of diagonally connected containers, a shaft connected to said containers to produce a gyratory movement, a pin set eccentrically to said shaft and extending downwardly and resting in a step-bearing whereby the weight of said shaft is supported, a fixedly mounted 90 driver surrounding the axis of rotation, and a bearing for said driver mounted adjacent to the step-bearing carrying the pin.
57. In combination, two pairs of diagonally connected containers, means whereby 100 said containers are suspended, bearings arranged between said containers, a shaft mounted in said bearings, an eccentric pin on said shaft, a step-bearing supporting said pin, a fixedly mounted driver adjacent 105 said step-bearing and surrounding the axis of movement, and a yielding connection between said driver and the shaft.
58. In combination, two sets of diagonally connected containers, a support independent of said containers, a laterally movable, vertically positioned shaft engaging the containers and said support, a fixed bearing surrounding the axis of movement of said shaft, a driver mounted in said bearing, and yielding connections between said driver and the shaft, whereby the latter may be driven from the former notwithstanding the difference between the axis of rotation of the driver and the axis of rotation of said shaft.
59. In combination, two sets of diagonally connected containers, suspending means therefor, bearing members arranged centrally of each set of containers, a laterally movable rotatable stem engaging said bearing members, a step-bearing for said stem, a driver having a central opening

through which said stem extends but is free of contact therewith, and a bearing in which said driver is mounted.

60. In combination, two sets of diagonally connected containers, supporting means therefor, orbitally movable means for gyrating said containers, and a steadyng device comprising a laterally movable member supporting the gyrator means.

61. In combination, two sets of diagonally connected bodies, a gyrator for said bodies, a yielding steadyng device to restrain the bodies from abnormal throw, a driver, and a transmission device between the gyrator and the driver, said device being slidable laterally to the driver.

62. In combination, two pairs of diagonally connected bodies, supporting means for said bodies, an independently supported gyrator for said bodies, and a slidable device concentric with and engaging said gyrator to steady the same.

63. In combination, two pairs of diag-

nally connected bodies arranged to have a gyratory movement, a driver therefor, a shaft thereto, a pin whose axial line is different from that of the shaft but operably connected therewith, a support upon which said pin rests having a friction surface over which said pin may move, and a bearing block interposed between said pin and the surface of said support.

64. In combination, two pairs of diagonally connected suspended bodies arranged to have a gyratory movement, a driver therefor, a shaft thereto, a pin set eccentric to said shaft, and frictional means coacting with the eccentric pin for restraining abnormal throw of the suspended bodies during gyration.

In testimony whereof I affix my signature, in the presence of two witnesses.

GEORGE W. COMBS.

Witnesses:

S. ANDERSON.

K. H. SHEIDENBERGER.

It is hereby certified that in Letters Patent No. 1,123,167, granted December 29, 1914, upon the application of George W. Combs, of Leavenworth, Kansas, for an improvement in "Gyratory Structures," errors appear in the printed specification requiring correction as follows: Page 5, line 107, for the word "driven" read *driver*; page 7, line 46, name of the second-mentioned witness, for "K. H. Sheidenberger" read *G. H. Sheidenberger*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
